UNITED STATES PATENT OFFICE.

STANISLAW SALA AND KAROL DABROWSKI, OF HAMTRAMCK, MICHIGAN.

DESIGN FOR A POLYCYCLE.

57,993.

Specification for Design.

Patented May 24, 1921.

Application filed November 18, 1920. Serial No. 425,002. Term of patent 7 years.

To all whom it may concern:

Be it known that we, STANISLAW SALA and KAROL DABROWSKI, citizens of Poland, residing at Hamtramck, in the county of Wayne and State of Michigan, have invented a new and original and ornamental Design for Polycycles, of which the following is a specification, reference being had to the accompanying drawing, forming part thereof.

Figure 1 is a view in side elevation of a polycycle, showing our new design,

Fig. 2 is a top plan view thereof, and

Fig. 3 is a rear elevational view of the same.

We claim:

The ornamental design for a polycycle, as shown.

STANISLAW SALA.
KAROL DABROWSKI.
